UNITED STATES PATENT OFFICE.

ALBERT J. GIFFORD, OF WORCESTER, MASSACHUSETTS.

PAPER-CLIP.

1,152,406.

Specification of Letters Patent.

Patented Sept. 7, 1915.

Application filed October 20, 1908. Serial No. 453,596.

To all whom it may concern:

Be it known that I, ALBERT J. GIFFORD, a citizen of the United States, residing at Worcester, in the county of Worcester and 5 State of Massachusetts, have invented a new and useful Paper-Clip, of which the following is a specification.

This invention relates to a spring clip for use in holding papers and similar articles. 10 The principal object of the invention is to provide a simple and inexpensive clip comprising a plurality of members of a similar shape made without bends or folds so that it can be manufactured in a rapid and inexpensive manner by the rotary process; that is by winding the wire helically and continuously on a mandrel and cutting each alternate coil so as to separate the wound wire into a plurality of clips each consisting of 15 two or more coils.

Further objects of the invention are to provide for constructing the clips with greater economy in the use of wire and generally to simplify and improve clips of this 20 character as will be set forth hereinafter.

Reference is to be had to the accompanying drawing which shows one form of the invention and in which,

Figure 1 is a perspective view of a mandrel showing how the wire is coiled thereon to make one form of clip, and Fig. 2 is a perspective view of a clip made on the mandrel shown in Fig. 1.

The clip is preferably made of wire of any 35 desired size and form having such temper as to provide the necessary resiliency.

The clip as completed consists of members *a* and *b* which may be superposed on each other. I have shown an article made with 40 only two members *a* and *b* but it is obvious that the invention is not limited to a construction having only two members. The two members are of similar shape each constituting a figure, preferably of regular 45 form, but incomplete on one side. This is done by providing cross bars *c* and *d* which extend across the figures and which terminate in ends *e*, *f* and *g*, *h* respectively. When made in the general form of a circle this produces a segmental or D-shaped figure. As 50 will be explained hereinafter, the adjacent ends *e* and *g* of the two cross bars are formed at the same place on the mandrel on which the wire is wound and are displaced circumferentially by the natural recoil of the wire when the wire is removed from the man-

drel so as to assume the position shown in Fig. 2. The ends of the wire *k* and *l* are formed originally exactly in line with each other on the mandrel but when this recoil 60 takes place in removing the clip, these ends separate. Now in the form shown in Fig. 2, which is of a general circular shape, this separation takes place along the circumference of the circle and it will be seen that the diameter bisecting the distance between the two ends *k* and *l* will cut the other side of the member in such position that the adjacent ends *e* and *g* of the two cross bars will lie on the same side of that diameter. 65 The same is true of the other two ends *f* and *h* as will be understood without further explanation. It will be seen also that each member of the clip is shown as symmetrical with respect to a line normal to the center of 70 its cross bar. The recoil of the wire, it will be seen, results in bringing one of the left-hand ends *e* of one member toward the opposite right-hand end *h* of the other and carries the other two ends away from each 75 other circumferentially. This results in bringing the two chordal cross-bars *c* and *d* into an angular position with respect to each other, crossing at their centers when the figure is symmetrical. This furnishes 80 the necessary jaws for gripping the paper or other material which is to be held and provides a most convenient construction for 85 this purpose.

It will be seen that the clip is of such 90 form as to bring the cross-bars entirely within the circumference or periphery and avoid the provision of any extending loops, folds, bends or projections. This has several important results. In the first place 95 by cutting down the length of the periphery of the figure, it materially reduces the amount of wire employed, which is no small item in an article of this class, as on account of the cheap mode of manufacture which 100 will be described, the cost of the wire is the principal item of expense; second, articles having the same resiliency as those which are made with extending bends, etc., and having the same holding force, occupy 105 less space so that they can be packed more economically; third, all projecting loops and the like which tend to tangle up the articles when packed promiscuously are avoided; and fourth, a more compact, neat 110 and attractive appearing article is provided.

One of the great advantages of this invention is in the simplicity of the mode of manufacture. By reference to Fig. 1 it will be seen that the wire is coiled upon a simple mandrel *n* which gives the shape which it is desired to have the article assume. In order to form an article such as that shown in Fig. 2, the mandrel is of a general cylindrical form with one side cut away, as on a chord, to give a flat surface *o* at one side. It will be seen that the mandrel has absolutely no projections and no irregularities except this flat side and consequently it is most cheaply made and easily manipulated in the manufacture of the article. In order to produce a clip of some other form, the mandrel is correspondingly modified, but as there is no necessity of providing it with any projection, it will be seen that in order to carry out this invention to produce the article, a simple mandrel may be used, and that the mandrel alone gives the entire shape to the article as no additional bending operation is required. Now in the manufacture of the clip shown, the wire is simply wound on the mandrel helically in a well-known manner and it is then clipped on every alternate coil. The clipping is done at a point substantially opposite the cut away surface *o* of the mandrel. Now it is well known in this art that when the coil comes off the mandrel the natural recoil of the wire will operate to move the convolutions slightly with respect to each other circumferentially. In this invention, the recoil is taken advantage of for the purpose of bringing two opposite ends of the cross bars, as for instance *e* and *h*, toward each other instead of separating them and thus producing two jaws which are formed at different points on the mandrel. When clips were made in the old way, it is obvious that the manufacturer had absolutely no control over the distance between the projecting loops on his clip except in so far as he had control of the temper and resiliency of the wire. Therefore, the wire had to be of a certain quality of temper and if wire of some other temper was used, the article would be of a different shape. The jaws would be nearer together if the resiliency of the wire were less, so that the article would be useless for this purpose if wire was used below a certain temper. No such difficulty is presented with this invention because the resiliency is depended upon merely to bring the end *e* toward the end *h*. Now if the resiliency of the wire is less than it should be, the two cross bars will not cross at as great an angle and their ends *e* and *h* will not be brought as near each other. This merely gives a greater opening between the wires. Another point to be ob-

served is that the flat or other shaped surface *o* of the mandrel can be made as narrow or as wide as may be desired up to the diameter of the mandrel, and consequently the angular position of the cross bars will be regulated by the shape of the mandrel itself in addition to the resiliency of the wire. In this way, I have two ways in which I can control the shape of the article to be produced instead of depending entirely upon the resiliency or temper of the wire.

While I have illustrated and described a certain preferred form of the invention and the mode of making it, I am aware that many modifications may be made therein by any person skilled in the art without departing from the scope thereof as expressed in the claims. Therefore, I do not wish to be limited to the particular details of construction and steps of the process described, but

What I do claim is:

1. As an article of manufacture, a clip comprising a plurality of members identical in shape and size formed of a continuous resilient wire, each substantially in the form of a D-shaped figure having a straight bar extending across it and an incomplete curved part, said bars being offset so as to cross each other within the figure, and each figure being symmetrical with respect to a line normal to the center of its said bar, whereby all parts of the clip are contained within a circular space of the periphery of which the curve of each D-shaped figure forms a part.

2. A clip consisting of a plurality of integrally connected nearly complete substantially D-shaped superposed resilient metallic members, each having a chordal cross-bar located entirely within the periphery of the members, each being symmetrical with respect to a central line normal to the cross bar thereof and each of the same shape, said cross-bars being offset in opposite directions, one end of one cross-bar being brought toward the opposite end of the other cross-bar so as to cross each other and constitute a pair of jaws located within the periphery of both members, the other two ends being separated and located substantially on the peripheries of both members, the adjacent ends of the two bars lying on the same side of the diameters which bisect the distance between the free ends of the wire.

In testimony whereof I have hereunto set my hand, in the presence of two subscribing witnesses.

ALBERT J. GIFFORD.
